UNITED STATES PATENT OFFICE.

MAX BREMER, OF NEW BEDFORD, MASSACHUSETTS.

HANDLE FOR COFFINS.

SPECIFICATION forming part of Letters Patent No. 444,973, dated January 20, 1891.

Application filed September 25, 1890. Serial No. 366,073. (No model.)

To all whom it may concern:

Be it known that I, MAX BREMER, of New Bedford, in the county of Bristol and State of Massachusetts, have invented an Improved 5 Casket-Handle, of which the following is a specification, reference being had to the accompanying drawings, forming part hereof, in which—

Figure 1 is a lengthwise section of one style 10 of one handle. Fig. 2 is a like section of another style.

Casket-handles to suit the trade must be ornate, sufficiently strong, and not too expensive; and the object of my invention is to 15 provide handles uniting these three requirements.

My invention consists in a handle composed 20 of two arms and a bar or hand-piece, each arm having a ring at its end through which the 25 bar passes in the usual way; but in my handle there are two or more ornamental sleeves between the two rings.

In the drawings, A A' are the arms, which 30 are of the usual construction—that is, each arm is hinged to a lug a and each arm has upon it a ring a'. The bar B is passed through the rings a' and properly secured to them, commonly by screws a². In my improved 35 handle the bar B is formed of a rod b, usually 40 of wood, and two or more ornamental sleeves b' b², which fit upon the rod b between the rings a'. The sleeve b' is shown as a swell symmetrical with the swell b², which may be either integral with rod b or a sleeve like b', 45 this being a mere question of cost; but the middle swell b² is a sleeve usually of metal, celluloid, or like ornamental material, or when of wood is covered with a covering which is ornamental and forms a contrast with the 50 covering of the swells b' b², the characteristic feature of my invention being that the handle between the rings a' is divided into two distinct parts b' b² by a third dissimilar part b², and in order to attain this result practically

I make the parts b' and b² in the form of 45 sleeves which fit upon the rod b, and while the part b² may also be a sleeve like b', yet it is practically as well to make b and b² integral when the parts b, b', and b² are all of 50 wood covered with a textile fabric, as in the handle shown in the drawings. When b' and b² are of metal, celluloid, or the like, they will of course be separate from b, which is in 55 practice a rod of wood; but, as shown, b' is a wooden sleeve covered with a textile material, and b² is a swell turned on b and covered with the same material. The sleeve b² is recessed at each end, so that it overlaps the end of the swells b' b². This is desirable, even if all these parts b' b² b³ be of ornamental material, such as metal, celluloid, or 60 the like; but is especially so when the swells b' b² are of wood covered with textile fabric, for then the recessed ends of the swells b' b² 65 cover the raw edges of the textile fabric. 65

In one style of my handle (that shown in the drawings) b' and b² are of wood and covered with broadcloth, plush, or the like, and b² is a sleeve of polished metal; but in other styles b' and b² are both of wood, b' and also 70 b² being covered with, say, broadcloth, and b² with satin or some other covering contrasting with the covering of b' and b². In this case b² may be integral with rod b, when b' and b² 75 must be sleeves fitted upon rod b. 75

What I claim as my invention is—

The improved casket-handle above described, composed of two arms provided with rod-receiving rings, a rod mounted in the rings, and two sleeves upon the rod and between 80 the rings and of outer diameters greater than the inner diameters of the rings, substantially as and for the purpose set forth.

MAX BREMER.
